UNITED STATES PATENT OFFICE.

GEORGE A. WHEELER, OF NEW YORK, N. Y.; H. M. WHEELER ADMINISTRATOR OF SAID
GEORGE A. WHEELER, DECEASED.

MOVING STAIRWAY.

1,130,555.

Specification of Letters Patent.

Patented Mar. 2, 1915.

Application filed November 16, 1909. Serial No. 528,426.

To all whom it may concern:

Be it known that I, GEORGE A. WHEELER, a citizen of the United States, residing in the borough of Brooklyn, Kings county, in the city and State of New York, have invented new and useful Improvements in Moving Stairways, of which the following is a specification.

My invention relates to certain improvements in mechanism of the particular class described and claimed in my U. S. Patent No. 888,949, May 26th, 1908, one object of the present invention being to simplify the construction and reduce the space occupied by such mechanism.

Another object of the invention is to improve the device as to safety.

A further object is to provide a simple drive for the device and one that will economize power and utilize the weight of the descending load in raising the ascending load.

These and other advantageous ends I secure by the constructions hereinafter set forth, reference being had to the accompanying drawings in which—

Figure 1 is a plan, to some extent diagrammatic, of a moving stairway constructed in accordance with my invention; Fig. 2 is a diagrammatic vertical section on line 2—2 of the stairway illustrated in Fig. 1; Fig. 3 is a diagrammatic vertical section on line 3—3, Fig. 1; Fig. 4 is an isometric view of one of the carriages or steps; Fig. 5 is a similar fragmentary view in detail of the upper portion of a carriage or step; Fig. 6 is a vertical section through the upper parts of two of the carriages and illustrates different relative positions; Fig. 7 is a detailed side view and Fig. 8 a detailed plan, partly in horizontal section, of the stairway illustrated in Figs. 1, 2 and 3; Figs. 9, 10 and 11 comprise a transverse section, side elevation and horizontal sectional plan, respectively, of my improved stairway and illustrate more particularly the driving mechanism; Fig. 12 is a detailed view of three of the steps or carriages in operative position on the inclined guides; Figs. 13 and 14 are views similar to Figs. 7 and 8 but illustrate a modified form of my device; Figs. 15 and 16 are views similar to Figs. 9 and 11, and illustrate a modified form of driving mecha-

nism; Fig. 17 is an isometric fragmentary detail of a modification fully explained hereinafter.

Referring first to Figs. 4, 5, 6, 7 and 8 of the above drawings, which show one embodiment, preferred for the purposes of illustration, my improved stairway consists of a series of carriages or steps A, each mounted upon a pair of wheels a journaled alternately upon two sets of axles a¹ and a² which are preferably arched in form and broadened at the middle into a substantially rectangular plate, in each of the four corners of which are holes a³ with an additional hole a⁴ at the center where the plate is preferably thickened to form an annular flange around the hole a⁴. The axles a¹ and a² differ only in length, the axles a¹ being enough longer than the axles a² so that the wheels on the former do not track with the wheels on the latter; otherwise all the steps or carriages A are alike. Extending upward through the holes a³ are four similar rods a⁵ which also pass through four similar holes in each of the bearing blocks a⁶, a⁷, a⁸, a⁹ and a¹⁰ that are superimposed, one above another, upon the axles a¹ and a², and thus form a rigid built-up standard for the support of a framework to which the tread and two similar risers of each carriage or step are attached. The lower bearing block a⁶ contains a half socket, and the bearing block a⁷ contains a half socket on both its upper and under sides, the half socket on its under side registering with the half socket in block a⁶ and forming a bearing a¹¹ for a ball. In like manner the block a⁸ has a half socket on both its upper and under sides, the half socket on its under side forming, with the half socket on the upper side of a⁷ before mentioned, another bearing a¹¹ for a ball. In the same manner a third and a fourth bearing a¹¹ is formed by half sockets in the bearing blocks a⁹ and a¹⁰, the block a¹⁰, like the block a⁶, having but one half socket. In some cases I may make the block a⁶ integral with the axles and the block a¹⁰ integral with the framework next to be described. Leading from the sockets or bearings a¹¹ are openings a¹² occurring alternately on opposite sides of the standard formed by the superimposed blocks. One vertical side a¹³, of the openings a¹², is at

2

a right angle with the axles a^1 and a^2 , while the opposite vertical side a^{14} is at a different angle with the axles, being splayed outwardly; the upper side a^{15} and the lower side a^{16} of the openings a^{12} are also splayed outwardly. These four sides of the openings a^{12} each forms a stop for a purpose mentioned hereinafter. Resting upon the built-up standard, above described, is a framework, preferably of cast metal, consisting of four similar hubs a^{17} connected by webs a^{18} and carrying projecting plates a^{19} . Through holes a^{20} in the centers of the hubs a^{17} pass the rods a^5 thereby securing the framework rigidly to the standard. Each carriage or step A, moreover, comprises a tread having a riser along each of its opposite longitudinal edges, and may be built up, as is clearly shown in Figs. 5 and 20 6, of two similar but oppositely placed sheet metal stampings bent to form the longitudinal edges a^{21} of the tread and the risers a^{22} . The risers a^{22} are formed with a longitudinal ridge, about their middle height, for 25 the purpose of stiffening the depending plates which are thus shaped into two planes, meeting to constitute an angle, made exterior so as to provide clearance for the forming tools. The risers a^{22} preferably 30 terminate at either end in buffers a^{23} which may be formed from the metal sheet or else of metal pieces suitably fastened on. The stampings, where they constitute the edges of the tread, are preferably grooved or 35 roughened to prevent slipping.

For the purpose of securing the stampings rigidly to the framework above described, the side of the stamping opposite the riser is bent down parallel with the upper plane 40 of the riser and then substantially at right angles thereto, forming a flange a^{24} which is punched or drilled with holes, two in each stamping, through which the rods a^5 pass and is clamped down tightly by the locking 45 nuts a^{25} . The projecting plates a^{19} are of such shape as to fit closely against the rear sides of the stampings which may be secured to them by tap screws or the plates a^{19} may be flanged and bolted to the stampings. 50

Between the two stampings, above mentioned, the tread of the carriages or steps A may be formed of a piece of wood a^{26} with the end edges protected by metal strips a^{27} 55 screwed on. The wooden piece a^{26} may be secured in place by screws entering wooden strips a^{28} located underneath and screwed or bolted to the flanges through holes made in both.

60 On the under side of the axles a^1 and a^2 of the carriages, in the opening of the arch, is journaled a roller a^{29} upon a shouldered pin a^{30} , inserted in the hole or bore a^4 and secured in place by a cotter pin a^{31} or other 65 means. The roller a^{29} is so mounted that its

tread is in a horizontal line with the axles of the supporting wheels a of the carriages A.

The several carriages or steps A are connected into an endless jointed structure by 70 means of links B and the sockets or bearings a^{11} , each link B terminating at either end in a ball b , which passes through an opening a^{12} and is journaled in one of the sockets a^{11} , as is clearly shown in Figs. 7, 8 and 12. 75 There are two of these links between each pair of carriages or steps, making four links whose terminals are journaled in the four sockets a^{11} of each built-up standard, the bottom and third sockets receiving the balls 80 of the pair of links connecting one adjacent standard, and the second and fourth sockets receiving the balls of the pair of links connecting the other adjacent standard. Thus each pair of links is attached in parallelism, 85 one over the other. The uppermost link of the last mentioned pair preferably has a V-shaped offset b^1 in order to provide clearance for the risers a^{22} , although this offset can be omitted and the links be all alike by 90 stiltting the carriages somewhat more.

The guideway for the jointed traveling structure, as is clearly shown in Figs. 1, 2, 3, 7, 8 and 9, comprises ascending and descending portions upon which the carriages or 95 steps form flights X, and preferably horizontal portions at top and bottom on which the carriages form landings Y, and looped portions Z connecting the horizontal portions into an endless way, the track or guideway on the looped portions being arranged in an improved manner and one that permits of turning, without interference, rigid carriages in a space small in all dimensions. As it is not necessary or desirable to use the 100 carriages when on the loops Z, this portion of the stairway is covered over by a stationary platform D. The remaining or exposed portions of the stairway are designated as carrying runs. 110

While for the purposes of illustration, I have shown but one general arrangement of flights, landings and loops, it is to be understood and will be obvious to those skilled in the art, that the various types of stairways 115 shown in the patent mentioned in the second paragraph of this specification, as well as still other types or arrangements, may be used with my present construction; and that the type of stairway selected would necessarily depend largely upon the location. 120

The strings or framework for the support of the tracks consists preferably of two built-up channels C, Figs. 7 and 9, supported in any usual or suitable way. There are two 125 rails, c and c^1 , attached to each channel C, and located in such relative vertical planes as to engage with the wheels a of the long and short axles, a^1 and a^2 respectively, of the two series of carriages. On the flights 130

X of the stairway, the treads of the rails c and c^1 are in a single plane of such inclination that the carriages are retained with the bottoms of the buffers a^{23} in contact, and 5 with the side edges of the links B in contact with the sides a^{13} of the openings a^{12} in the bearing blocks; and with the upper sides a^{15} of the openings a^{12} of the carriages having the long axles a^1 , and the lower sides a^{16} of 10 the openings a^{12} of the carriages having the short axles a^2 , in contact with the upper and lower edges respectively of the adjacent links B, thus locking the individual carriages in alinement both laterally and vertically, as is clearly shown in Fig. 12. Similarly on the landings Y, the carriages are locked against lateral displacement by the contact of the juxtaposed tops of the buffers a^{23} , and of the stops a^{13} with the links B; 15 and also against vertical displacement through the parallel links B.

In order to permit of rigid rectangular carriages like A passing around the loops Z, it is necessary for them to lap each other 20 obliquely and, in my improved form of loop, I locate the rails c and c^1 in two such relative horizontal planes that alternate carriages overlap and underlap each other respectively, as is clearly shown in Figs. 1, 2, 3, 7 and 8, 25 the rails c^1 , with which the wheels of the carriages having the short axles a^2 engage, being inclined downwardly, before the loop is reached, by sections of rail c^2 sufficiently long and enough steeper than on the flights 30 to cause the carriages with the axles a^2 to take relative positions in which they are below and clear of the carriages having the axles a^1 whose rails c continue around the loops Z preferably in the same horizontal 35 plane as on the landings Y. Thus the carriages with the axles a^1 are free to swing over, and the carriages with the axles a^2 under, each other respectively; and the sides a^{14} of the openings a^{12} in the bearing 40 blocks are at such an angle as to contact with the side edges of the links B and retain the carriages in radial positions on the curved rails of the loops Z, which, measured 45 on the chain line, are preferably of such radius, relative to the distance from center to center of the ball sockets a^{11} , when the carriages are lapped, that the carriages are in radial position when they enter or leave the loops Z, as well as when they are traveling 50 thereon; and the upper sides a^{15} and the lower sides a^{16} of the openings a^{12} of the carriages having the short and long axles respectively, that are out of contact with the links B on the flights, Fig. 12, are 55 splayed at such an angle as to be in contact with the links on the loops Z, thereby operating with the stops that are in contact 60 on the carrying runs, and with the radial stops a^{14} , to lock the treads of the carriages 65 in rigid horizontal and lateral alinement,

through the two separated endless lines of parallel links B which lie in the same vertical planes and whose bearings are centered vertically over each other in every position of the carriages. The rollers a^{29} to which 70 the drive is applied, as hereinafter described, are mounted on a line with the axles or axes of the carriages and thus the driving mechanism has no tendency to tilt the treads of the carriages from the horizontal. 75

In order to supplement gravity in holding the wheels a of the long and short axles a^1 and a^2 to their respective rails c and c^1 , guard rails c^4 and c^5 are located above the 80 rails c and c^1 , respectively, and are extended, on both sides, around the loops Z.

After the carriages have traversed a loop Z, it is necessary that the carriages with the short axles a^2 be raised to the level that they 85 were on before entering the loop, i. e., the level of the landing Y of which they form a part. Hence the rails c^1 , beyond the loop, are inclined upwardly by short sections of rail c^3 , corresponding with the sections c^2 , 90 until their level coincides with that of the rails c .

As will be seen by reference to Figs. 7 and 8, the junctures between the inclined and horizontal rails, both at the beginning 95 and ending of the landings and of the loops, is angular which shape tends to cause a variation in the tension of the belt of carriages, due to changes in position of the links in relation to the rails at these points, 100 e. g., when two adjacent pairs of links are parallel with the rails c and c^2 respectively, as in Fig. 7, the links nearly coincide in length with the rails, but when a pair of links is across an angular juncture, the coincidence in length is destroyed and the tension affected. By proportioning or adjusting the lengths of the rails intermediate of these junctures, I may so locate them that 105 these two described positions will alternate 110 at each or any two adjacent pairs of junctures, thereby insuring a practically uniform tension in the belt of carriages.

As will be seen by reference to Fig. 6, which illustrates three relative positions of 115 adjacent carriages or steps, the risers a^{22} are nowhere in contact and the space formed between the carriages on the landings, while not enough to admit the tip of a crutch or cane used for support, is yet wide enough 120 to allow of skirts lifting out in case their edges should fall therein, and thereby preventing them from being caught, as occasionally happens when the path of contiguous edges of the steps or carriages is such 125 as to fit the risers closely in changing from the incline to the horizontal or, vice versa, from the horizontal to the incline.

For the purpose of driving the endless belt of carriages, I provide the screw gear E 130

so mounted as to engage with the rollers a^{29} on the carriages A. I preferably drive both the ascending and the descending runs of the stairway, providing the screw gear E, 5 Figs. 9, 10 and 11, on the ascending side and the corresponding screw gear E^1 on the descending side. The shafts for the gears E and E^1 are carried in suitable bearings e and e^1 respectively and are provided 10 with bevel gears e^2 and e^3 meshing with the bevel pinions e^4 and e^5 respectively on a shaft e^6 which is carried in suitable bearings e^7 and reaches across from one landing or flight of one run to the landing or flight 15 of the other run. The two bevel pinions e^4 and e^5 are so mounted, of course, as to drive the gears with which they mesh, and consequently the gears E and E^1 , in opposite directions.

20 The screw gears E and E^1 are preferably similar and of such length and pitch as to retain the rollers a^{29} of at least two adjacent carriages on both runs in engagement at all times; and the screw gears are so located as 25 to take the strain of the descending load off the portion of the belt on the loop Z and transmit it, through the shaft e^6 , to the ascending run where it is utilized in the gear E to assist in raising the ascending load. I 30 may provide similar gearing for the bottom of the stairway. This arrangement of drives leaves the carriages on the loops free to vary their speed to suit the varying positions of the carriages thereon. Where conditions require, I may provide additional drives intermediate of the ends of the stairway.

In Figs. 13 and 14, I have shown a modification of the loop construction. In this form, instead of the rails c^1 being 40 pressed, the rails c are elevated a corresponding distance, while the level of the rails c^1 remains unchanged, thereby causing the carriages with the long axles a^1 to rise in order to permit of the previously described 45 overlapping and underlapping, the platform D being elevated a corresponding distance. These figures also illustrate another modification of the loop, which is applicable to both forms, namely the employment of an 50 arc or turn other than 180° , in this case 90° , which may be utilized, either to locate one of the runs at an angle with the other, in this case at a right angle, or to introduce a straight section into the loop which, after 55 being continued the distance that the situation requires, may terminate in another arc or turn, bringing the other run at any desired angle with or distance from the first run.

60 In each form, in order to safeguard passengers, I preferably employ a device located at the points where the carriages pass under the fixed platforms, indicated in Figs. 1, 2, 3, 7, 9 and 13, and described by me in 65 a former patent (No. 479,864, Aug. 2, 1892).

It is also to be understood that my improved stairway would be flanked, preferably on both sides, by the usual moving handrails which or the casings therefor, are indicated in various figures.

The left hand carriage or step in Fig. 12 illustrates a method that I preferably employ for automatically lubricating the sockets which form bearings for the balls of the links. A reservoir H for lubricant is located 70 underneath the tread of the carriage, above the center of the sockets a^{11} , with a pipe h leading to a duct h^1 in the upper bearing block and additional ducts h^1 connecting the other sockets.

Figs. 15 and 16 illustrate a modification of the drive. The common driving shaft f^2 , instead of being at an angle, may be parallel with the shafts of the screw gears F and F^1 , 80 corresponding to the screw gears E and E^1 , and the screw gears driven from this shaft by suitable chain or other belts f and sprockets or pulleys f^1 . In this form of drive the screw gears F and F^1 are similar but have oppositely turned threads, one being right hand and the other left hand, thereby reversing the motion without the use of bevel gears.

In Fig. 17 I have shown the blocks containing the ball sockets for the links constructed of pressed metal such as sheet metal stampings, which have sockets m with openings m^1 pressed into the metal, and the stampings are secured in place on the rods a^5 by having holes punched or drilled in 100 them and being blocked up with the separators m^2 .

While I have shown and described a suitable method, or methods of constructing and arranging my improved stairway, I do not 105 limit myself to the specific constructions or arrangements shown or described, since the scope of my invention embraces numerous modifications of which the described constructions or arrangements are typical.

What I claim is—

1. In a device of the class described, the combination of substantially straight ascending and descending runs connected by curved runs, carriages arranged to travel on said runs, the curved portions of the runs being so shaped that alternate carriages will obliquely overlap and underlap respectively in passing around the curve, substantially as described.

2. The combination, in a device of the class described, of endless guides, a series of carriages arranged in an endless chain, said guides having straight portions and curves, the curved portions in part diverging from a single vertical plane, and being so laid out that alternate carriages will underlap the others in passing around the curves, substantially as described.

3. The combination, in a device of the

- class described, of substantially straight guides and curved lateral guides, carriages arranged to travel on said guides, the guides being so arranged that each alternate carriage only will move to a position on a different level from that of the succeeding one before turning, substantially as described. 5
4. In a device of the class described, a plurality of carriages mounted upon anti-friction devices and comprising more than one series intermingled in a regular order, the supporting devices of each series being attached in such relative planes as not to track with those of another series, guides for 10 the supporting devices of each series and consisting of substantially straight horizontal and inclined portions and laterally curved portions connecting the substantially straight portions into an endless way, the guides on the curved portions being so arranged as to cause the series of carriages to overlap and underlap each other respectively in passing around the curves, substantially as described. 15
- 20 5. In a device of the class described, a plurality of carriages, each mounted upon a single pair of wheels, and comprising two series intermingled in a regular order, the wheels of one series being attached in such vertical planes as not to track with the wheels of the other series, tracks for the wheels of each series, said tracks consisting of substantially straight horizontal and inclined portions and laterally curved portions, connecting the substantially straight portions into an endless way, the tracks on the curved portions being in such relative horizontal planes as to cause the two series of carriages to overlap and underlap each 25 other respectively in passing around the curves, substantially as described. 30
- 40 6. In a device of the class described, a guideway consisting of substantially straight horizontal and inclined portions and laterally curved portions connecting the substantially straight portions into an endless way, two rails on each side of said substantially straight portions disposed in the same horizontal and inclined planes respectively, and continuing rails on the laterally curved portions disposed in different horizontal planes, with carriages arranged to travel on said rails, substantially as described. 45
- 50 7. In a device of the class described, comprising a guideway consisting of substantially straight portions and curved portions, intermingled series of carriages said series differing from each other in the length of their axles with wheels journaled on the 55 axles, substantially as described. 60
8. In a device of the class described, a series of carriages each comprising an axle supporting a standard which in turn supports a framework and attached thereto a tread portion formed of two oppositely 65
- placed metal stampings with risers integral therewith, and a filling in member between said stampings completing the tread portion, substantially as described. 70
9. In a device of the class described, a series of carriages each comprising an axle supporting a single centrally disposed standard which in turn supports a framework and attached thereto a tread portion, substantially as described. 75
10. In a device of the class described, the combination of a series of link connected carriages, each comprising an axle, a standard supported upon said axle and containing ball sockets, balls attached to the connecting links and journaled in the sockets, and a tread portion supported upon the standard, substantially as described. 80
11. In a device of the class described, a series of carriages connected by links having balls journaled in sockets on the carriages, said sockets being formed of metal stampings, substantially as described. 85
12. In a device of the class described, a series of carriages having risers composed of two planes meeting to form an exterior angle, substantially as described and for the purpose specified. 90
13. In a device of the class described, comprising horizontal and inclined carrying runs, a series of carriages adapted to form steps on the inclined run and a practically unbroken platform on the horizontal run, each carriage having a riser consisting of two planes meeting to form an exterior angle, said risers terminating at either end in buffers, substantially as described. 95
14. In a device of the class described, comprising horizontal and inclined carrying runs, a series of carriages adapted to form steps on the inclined run and a platform on the horizontal run, said carriages having risers terminating at either end in buffers, the said risers being arranged to be everywhere out of contact with each other and said buffers being arranged to abut against each other, on both of said runs, substantially as described. 105
15. In a device of the class described, the combination with a guideway comprising substantially straight inclined and horizontal portions and laterally curved portions, of a series of carriages adapted to travel thereon and to form steps on the inclined portions, practically unbroken platforms on the horizontal portions and to alternately overlap and underlap each other on the curved portions, and devices for locking said carriages in said relative positions, with means for driving the carriages, substantially as described. 110
16. In a device of the class described comprising straight inclined and laterally curved runs, link connected carriages arranged to travel on said runs, said carriages 120
- 125
- 130

being provided with stops to co-act with said links and lock the carriages against vertical displacement on the inclined runs, and also provided with other stops adapted to co-act with said links and lock the carriages against vertical displacement on the laterally curved runs, substantially as described.

17. In a device of the class described, a series of carriages each provided with a plurality of socket bearings, with a reservoir for lubricant located above said sockets and a duct leading therefrom to the socket bearings, substantially as described.

18. In a device of the class described, the combination with a connected series of carriages and a guideway therefor, of a screw driving gear mounted to engage with said carriages, said screw gear being of a suitable length and having its pitch adapted to the length of the connection between said carriages whereby a plurality of carriages

are in engagement with said gear at all times, substantially as described.

19. In a device of the class described, the combination with a series of carriages and a guideway therefor, comprising substantially straight carrying runs and laterally curved connecting runs, of means for changing the relative positions of the carriages at the beginning of the connecting runs, so that they will turn clear of each other while passing said connecting runs, and for restoring the alignment of the carriages after the connecting runs are passed, substantially as described.

In testimony whereof, I have signed my name to this specification, in the presence of two subscribing witnesses.

GEORGE A. WHEELER.
